UNITED STATES PATENT OFFICE.

JOHN B. WOOD, OF CRANSTON, RHODE ISLAND.

CAR-FENDER.

SPECIFICATION forming part of Letters Patent No. 681,361, dated August 27, 1901.

Application filed January 31, 1901. Serial No. 45,497. (No model.)

To all whom it may concern:

Be it known that I, JOHN B. WOOD, a citizen of the United States of America, and a resident of Oak Lawn, Cranston, in the county 5 of Providence and State of Rhode Island, have invented certain new and useful Improvements in Car-Fenders, of which the following is a specification.

My invention relates to improvements in 10 car-fenders, the same being of the type or class more especially adapted for street or tram-way cars; and it consists, essentially, of the suitably-supported endwise-slidable fender member proper having a rubber-protected or 15 resilient face or edge, an operating shaft or spindle located contiguous to the inside of the dashboard and extending downwardly through the platform, and a jointed movable connection uniting the said fender and spindle members, all as will be more fully hereinafter set forth and claimed.

I am well aware that many and various car-fenders have been devised; but as a rule such former devices, while possessing more or less 25 merit and utility, have been lacking in simplicity and conveniences and ease of operation. Moreover, the cost of construction has been such as to preclude their general adoption.

30 In my improved car-fender the objects sought to be attained are safety, efficiency, simplicity, lightness, ease and rapidity of action, and accessibility, all being obtained at a comparatively small cost. The arrangement 35 of the working spindle is such that a short angular movement of the operating lever or handle thereof suffices to project the fender to its limit in advance of the end of the car or to retract it to its normal position beneath 40 the car-platform.

Another advantage is that the device as a whole can be readily manufactured from structural steel or iron of staple or standard dimensions, there being practically no special 45 forgings required in its construction. I prefer to equip each end of the car with one of the fenders, the latter when retracted to its limit being substantially flush or even with the buffer usually present in modern street-cars. The operating-spindle extends upwardly close to the inner face of the dashboard and at a convenient height to be read-

ily manipulated in either direction by the motorman, the device being especially adapted for cars having vestibuled ends.

55

In the accompanying sheet of drawings, Figure 1 is a longitudinal sectional view taken substantially through the center of one end of a street-car, showing my improved car-fender projected as in use. Fig. 2 is an end view of the same. Fig. 3 is an inverted plan view corresponding with Figs. 1 and 2. Fig. 4 is a transverse section taken on line $x-x$ of Fig. 1, showing the manner of supporting the device; and Fig. 5 is a partial sectional view, 65 similar to Fig. 1, showing the relation of the several parts when the fender is in its normal or retracted position.

Again referring to the drawings, A designates the fender as a whole. The frame a of 70 the main or slidable member B of the fender is made of suitable angle-iron, bent to the desired shape or outline, its two sides or legs extending rearwardly and upwardly at an angle and slidably supported by the flanged 75 side plates or brackets b , firmly secured to the car-beams. (See also Fig. 4.) The front or outer end of the fender member B may be curved, as shown in Fig. 3. To the under side of the frame a is secured a curved transverse connecting-tie e , which in turn has riveted to it and to the frame a a series of thin flat parallel strips c of metal or other suitable material, thus forming a grid or surface adapted to receive and support any object 85 caught upon it. The outer or front end portions of these strips may extend beyond the frame a , each alternate one being bent downwardly and arranged to form between them an opening in which is mounted and secured 90 a piece of rubber r or other suitable resilient material, the ends being secured in sockets r' . (See Figs. 2 and 3.)

In lieu of one of the strips c I have substituted therefor at the center a piece f , the 95 same extending rearwardly and terminating in a vertical pin f' , adapted to pass through one end of a link or connection i , in turn jointed to a horizontal arm or lever s^2 , integral with or secured to the lower end of the 100 vertically-arranged operating shaft or spindle s . The latter extends through the platform p of the car and is supported in suitable bearings located contiguous to the in-

ner side of the usual dashboard *d*. The spindle *s* is surmounted with a crank-handle *s'*, through which the motorman is enabled to manipulate the fender. A spring-catch *s⁴* or 5 other analogous device may be used to maintain the handle, &c., in the extreme position.

To the front of the dashboard *d* are secured a series of vertically-arranged yielding bent strips *m* of metal, having the lower ends there- 10 of secured to the buffer-beam or cross-tie *n*. These strips *m* also serve as a fender or buffer, in that they form a resilient surface.

The car may be provided on the under side with the usual draw-bar *g*, pivoted or jointed 15 at *g'* to a forging secured to the buffer-beam *n*. The outer or free end of said bar is adapted to vibrate in the elongated curved opening formed in the fixed guide or quadrant *h*, substantially as common.

20 Assuming that a street-car is provided with my improved fender *A* and that the latter is in the retracted or normal position, (see Fig. 5,) the manner of operating the device may be described as follows: The motorman simply seizes the operating-handle *s'* and presses it rearwardly until it is arrested, say, by the dashboard *d*, at which instant the catch *s⁴* automatically springs into position and holds the member *s'* in place until the device is 25 again retracted. The act of thus swinging the handle rearwardly imparts angular movement to the spindle *s*, which in turn, through the medium of the link *i*, jointed thereto and to the pin *f'*, quickly and easily forces the 30 body or main member *B* of the fender outwardly and downwardly beyond the end of the car or to the position represented in Figs. 1 and 3, thus completing the operation. Obviously a reversal of the movement just 35 described will retract the fender to the normal position.

I may state that I prefer to locate the spindle *s* at a point near the brake-spindle, thus rendering it readily and conveniently accessible at all times, a comparatively small amount 40 of force being needed to effect its manipulation.

As hereinbefore stated, my improved car-fender is comparatively inexpensive in con-

struction. It is simple, light, and efficient and 50 is adapted to be easily and quickly manipulated. It can be readily attached to the usual framework of the car without material change, and is particularly well adapted for use on vestibuled cars, the construction and ar- 55 rangement of the device being such that the motorman can manipulate the fender with ease and without moving from the position assumed by him in operating the usual controlling-levers which actuate the power and 60 brake mechanisms.

I do not claim, broadly, as my invention a car-fender arranged to be tripped or released and shot forward by the act of manipulating a lever or other analogous means; nor do I 65 claim, broadly, a fender provided with a resilient guard; but

What I do claim, and desire to secure by United States Letters Patent, is—

1. The combination, in a car-fender, of inclined side brackets or hangers secured to the under side of the car-platform, the endwise-movable fender base or frame *B* supported by and slidably mounted in said brackets, a vertically-mounted operating-spindle located 70 contiguous to the rear side of the dashboard of the car and extending through the car-platform, and a connection uniting the said frame and spindle members; constructed and arranged whereby upon simply manipulating 75 the spindle the fender-frame is projected beyond the end of the car or retracted to its limit or normal position beneath the platform, substantially as shown and described.

2. The combination with the supported end- 80 wise-movable fender-base *B* having a central rearward extension *f*, of the mounted actuating-spindle *s*, located contiguous to the dashboard, having a horizontal arm *s²* secured thereto beneath the car-platform, and a link 85 or connection *i* jointed to and uniting the said members *f* and *s²* substantially as described.

Signed by me at Providence, Rhode Island, 90 this 29th day of January, A. D. 1901.

JOHN B. WOOD.
